PORTABLE, ILLUMINABLE MIRROR

David Bezborko, 255 W. 84th St. 10024, and Joseph Bezborko, 629 Kappock St. 10400, both of New York, N.Y.

Filed May 15, 1968, Ser. No. 11,953

Term of patent 14 years

Int. Cl. D6—06; D26—99

U.S. Cl. D86—1

FIG. 1

FIG. 2

FIG. 3

FIG. 4

FIG. 5

FIG. 6

FIG. 7

FIG. 8

FIG. 1 is a front elevational view of a portable illuminable mirror showing our new design;

FIG. 2 is a top plan view thereof, the cord portion being shown broken away for convenience of illustration;

FIG. 3 is a side elevational view of the mirror with the wing portions at right angles to the center portion;

FIG. 4 is a rear elevational view of the mirror as shown in FIG. 1;

FIG. 5 is a bottom plan view thereof;

FIG. 6 is a front elevational view of the mirror with the wing portions in a closed position;

FIG. 7 is a side elevational view thereof; and

FIG. 8 is a front perspective view of the mirror with the circular portion at an angle.

We claim:

The ornamental design for a portable, illuminable mirror, substantially as shown and described.
